WIRE TEST TUBE RACK

James William Farrough, Elkhart, Ind., assignor to
Miles Laboratories, Inc., Elkhart, Ind.

Filed Nov. 12, 1973, Ser. No. 414,925

Term of patent 14 years

Int. Cl. D6—04

U.S. Cl. D32—1

The sole figure is a perspective view of the wire test tube rack which embodies my new design.

I claim:

The ornamental design for a wire test tube rack, as shown and described.
